DESIGN FOR A VALVE

Edward J. Collins, West Los Angeles, Calif., assignor to Raymond T. Moloney, Chicago, Ill.

Application July 19, 1945, Serial No. 120,804

Term of patent 14 years

(Cl. D78—1)

To all whom it may concern:

Be it known that I, Edward J. Collins, a citizen of the United States and a resident of West Los Angeles, Los Angeles County, California, have invented a new, original, and ornamental Design for a Valve, of which the following is a specification, reference being had to the accompanying drawing, forming a part thereof:

Fig. 1 is a perspective view of the valve embodying my new design;

Fig. 2 is a front elevation of the same;
Fig. 3 is a side elevational view of the same;
Fig. 4 is a rear elevational view of the same;
Fig. 5 is an end view of the same.

The characteristic features of the design are shown in full lines.

I claim:

The ornamental design for a valve, as shown and described.

EDWARD J. COLLINS.
